UNITED STATES PATENT OFFICE.

JACOB B. YEAGLEY, OF INDIANAPOLIS, INDIANA.

SASH-TIGHTENER.

SPECIFICATION forming part of Letters Patent No. 247,728, dated September 27, 1881.

Application filed August 17, 1881. (Model.)

To all whom it may concern:

Be it known that I, JACOB B. YEAGLEY, a citizen of the United States, residing at Indianapolis, in the county of Marion and State of Indiana, have invented certain new and useful improvements in Weather-Proof Sash-Adjusters; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 This invention relates to certain new and useful improvements in weather-proof sash-adjusters for closing the sashes tightly against wind or rain by throwing the lower sash in two directions and pressing it tightly against the opposite side of window-frame and against the dividing strip or stop and lower cross-rail of upper sash; and to this end the invention consists in novel features of construction and combination and arrangement of parts, all as 25 will be hereinafter fully described, and specifically designated in the claim.

Figure 1 represents a side elevation of the lower sash and window-frame, showing the position of my improved sash-adjuster, and also 30 my improved lock and holder when the sash is closed down, the frame being broken away to show the locking-wheels. Figs. 2 and 3 are respectively detail views in perspective and section of the roller-plate and roller constituting my improved sash-adjuster.

In the drawings, A represents the curved rack-bar, and B C the cogged wheels journaled in the lever or key D, and by which they are adapted to be operated. E represents the pivoted lever or key catch, all of which constitute 40 my improved sash lock and holder above referred to.

My improved weather-proof sash-adjuster is composed of a roller-plate, F, secured to the lower sash by screws *ff*, as shown, and a rubber roller, G, mounted on a screw, *g*, which in the present instance is shown secured to the face-plate *d* of my improved sash lock and holder.

The plate F is secured to the side rail of the 50 lower sash, near the top thereof, and is bent as shown in Fig. 2, so that when secured to the sash it forms an inclined plane, over which the roller G moves or plays as the sash is pulled down, thus forcing it against the dividing strip 55 or stop and the lower cross-rail of the upper sash, while at the same time the oblique side flange, *h*, of roller-plate, coming in contact with the outer end of said roller G, will force sash tightly against the opposite side of the window-frame, thereby holding it tightly against 60 wind and rain, and also holding the upper sash tightly in position. As the sash is forced over toward the opposite side of window-frame it permits the large wheel B of my improved lock 65 and holder to drop down so as to properly engage the sash, and securing or locking it in position when closed.

The screw carrying the roller G should be long enough to allow the roller to play just beyond the vertical sash-head, and resting and revolving near or against it.

My improved sash-adjuster is used only for lower sash, as it will tighten upper sash, as above described, when both sashes are closed.

I do not wish to be understood as claiming, broadly, in the present case the parts constituting my improved sash lock and holder, as they form the subject-matter of a previous application.

Having thus fully described my invention, what I claim as new, and desire to secure by Letters Patent, is—

The herein-described weather-proof sash-adjuster, composed of a roller-plate, F, having 85 inclined plane and oblique side flange, *h*, and roller G, connected to sash and window-frame, respectively, substantially as and for the purpose herein shown and described.

In testimony whereof I affix my signature 90 in presence of two witnesses.

JACOB B. YEAGLEY.
